CLAIM

We claim the ornamental design for a correction type tape with a security pattern, as shown and described.

DESCRIPTION

FIG. 1 is a top view of the correction type tape with a security pattern showing my new design;

FIG. 2 is a bottom view thereof; showing the security pattern;

FIG. 3 is front view thereof;

FIG. 4 is a rear view thereof; and,

FIG. 5 is a side view thereof, the opposite side being a mirror image thereof.
